(Cl. D16—2)

To all whom it may concern:

Be it known that I, Harold F. Costello, a citizen of the United States of America, residing at the city of Detroit, in the county of Wayne and State of Michigan, have invented a new, original, and ornamental Design for a Vaporizer for Deodorant and Similar Tablets, of which the following is a specification, reference being had to the accompanying drawing, forming part thereof.

In the drawing

Fig. 1 is a side view of a vaporizer for deodorant and similar tablets, showing my new design;

I claim:

The ornamental design for a vaporizer for deodorant and similar tablets, as shown.

HAROLD F. COSTELLO.
